(54) **PENDULUM, BALANCE**

(76) Inventor: **Hiram Twiss**

*Hiram Swift of Meriden Connecticut
Seller's Patent*

The Schedule referred to in these Seller's Patent and making part of the same containing a description in the words of the said Hiram Swift himself of his improvement called "Swift's" improved balance pendulum.

To whom these presents shall come. Be it known that I Hiram Swift of Meriden in the County of New Haven in the State of Connecticut have invented constructed made and applied to use a new and useful improvement in the balance pendulum whereby the same may be adapted to regulate the movements of any clock or time piece either of wood brass or other metal, called "Swift's" improved balance pendulum. My improved balance pendulum consists in a bar of wood or metal armed with weights at each end falling about half an inch below the centre of motion either by driving in the bar or attaching the weight to the under side of it. The bar may be thirteen inches in length more or less, for common use armed with a ball of about three ounces weight at each end. This bar thus armed with weights is nicely and accurately balanced on an axis about this such as long exposing the bar on the centre of right angles. This axis may be supported at each end on knife edges on the under side placing in angular sockets, in which I place in points passing perpendicular to this the axis near each end otherwise inserted into the under side near the ends and projecting about one eighth of an inch. These edges or points should be of steel well tempered, and I have found on trial that the point of a well made drawing needle passed through the axis at each end to answer the purpose well.

These points are each to play in a female cut or hollow one sixteenth of an inch deep, one eighth of an inch broad at the top and having a flat surface one thirtieth of an inch diameter at the bottom also well tempered. The ends of the pendulum thus balanced, vibrates up and down with the least possible friction, and the balance pendulum thus improved is well adapted to regulate

the movements of any kind of clock or time pieces and may be connected in the following manner. This pendulum is supported on a stand or shelf near the bottom of the clock case. From the axis of the pendulum a wire rises, perpendicular about three inches long and passing through a loop at the lower end of a pendulum rod, which passes thro' the catch wire of the verge, thereby allowing the time wheels of the clock to move when the balance pendulum vibrates. A spring of rolled wire or other suitable material is also inserted into the axle and descends, perpendicular, about two inches into a regulator. The regulator consists of an angular socket of metal resembling the space between two large teeth of a saw inverted, about one sixteenth of an inch thick, this socket opens on the top about three fourths of an inch and is supported on a stud of metal about two inches long, rising from the bottom of the clock case directly under the axle of the balance and so as to permit the descending spring to touch the teeth of the socket at each vibration of the balance. The lower end of the stud is a screw passing through a nut resting on the bottom of the clock case and prevented from rising by a loop or bridge made fast to the bottom of the case through which the stud also passes, so that by turning the nut back to its place by the bridge, the stud will rise or fall and carry with it up or down the regulator which is guided by a mortise thro' which it moves in a plate of metal attached to the shelf which supports the pendulum, raising or lowering the regulator will accelerate or retard the vibrations. This improved pendulum will also regulate itself as to the effect of heat and cold, in as much as the expansion and contraction of this pendulum is counteracted by the corresponding contraction and expansion of the regulator. The balance pendulum above described is calculated for and regulate it so as to give forty four strokes in a minute, whereas the suspended pendulums in common use usually give ninety. This invention will lead to useful improvements in the construction of all time pieces regulated.

by the vibrations of pendulums. I do not claim as my invention a balance pendulum as such, but I do claim as my invention and improvement the mode of suspending the same as above described whereby. First the weight is placed on a single bar below the centre of motion thereby producing a repelling action on the balance. Second. In vibrating on knife edges or points whereby the friction is greatly reduced. Third in connecting it with a regulator by means of which the effects of heat and cold in the metal is counteracted, and also by means of which the spring of the balance pressing on the sides of the socket of the regulator assists the recoil of the balance when at the highest point of vibration and most disposed to remain at rest. In testimony that the foregoing is a true and full Specification of my improvement I subscribe these presents the twelfth day of Dec: 1833
